UNITED STATES PATENT OFFICE.

VERNON ROYLE, OF PATERSON, NEW JERSEY.

EDGING-MACHINE.

1,239,525.

Specification of Letters Patent. Patented Sept. 11, 1917.

Application filed April 30, 1915. Serial No. 25,063.

To all whom it may concern:

Be it known that I, VERNON ROYLE, a citizen of the United States, and resident of Paterson, in the county of Passaic and State 5 of New Jersey, have invented a new and useful Improvement in Edging-Machines, of which the following is a specification.

My invention relates to what is known in the art as an edger, for use in finishing 10 blocks and plates for the printing press, and is directed more particularly to the dimensioning gage and parts which intimately coact therewith, particularly a micrometer, the object being to improve the accuracy 15 and increase the output of the edger and at the same time leaving the edger free to be used independently of the improved gage.

A further object is to provide a micrometer as a unit capable of being used in connection with gages of other machines than 20 the edger.

In the accompanying drawings,

Figure 1 represents a plan view of a portion of the edger showing the parts in the 25 positions which they may assume in relation to a plate to be operated upon.

Fig. 2 is a side elevation of the work carrying table and parts carried thereby.

Fig. 3 is an enlarged detail side view of 30 one of the removable (pica) stops, showing a position of the same in broken lines thrown out of use.

Fig. 4 is a horizontal section through the same.

Fig. 5 is a transverse section of the same 35 taken in the plane of the line A—A of Fig. 4.

Fig. 6 is an enlarged transverse section taken in the plane of the line B—B of Fig. 1.

Fig. 7 is an enlarged detail elevation of 40 the auxiliary micrometer or measuring device.

Fig. 8 is a central section taken in the plane of the line C—C of Fig. 7, and

Fig. 9 is an enlarged transverse section 45 taken in the plane of the line D—D of Fig. 1.

The table on which the work is supported is denoted by 1. It is mounted on suitable ways to slide bodily with work thereon along the face of a cutter 2, in the present 50 instance a rotary cutter, the term "cutter" being used hereinafter to denote one or more cutting blades or edges as may be desired, the same forming, *per se*, no part of my present invention. The table 1 is made 55 large enough to accommodate the ordinary sizes of blocks and plates when the dimen-

sioning gage is in position thereon and unusually large sizes may be trimmed by removing the said gage, the removal requiring but a moment's time.

60

For holding the work at the front end, there is a clamp 3 provided and for holding the work at the opposite end, there is provided a sliding clamp 4 which presses the work to the table with a vise-like grip. The 65 specific structures of these clamps are not made features of the present invention.

The body of the dimensioning gage is denoted by 5. It is provided with an extended tongue 6 on its under side, which 70 tongue fits accurately in an elongated slot 7 in the table, the slot extending at right angles to the path in which the table moves, so that the gage body may be slid toward and away from the path of the cutter in a 75 right line. The slot 7 and tongue 6 are preferably tapered in cross section, as shown.

A rack bar 8, provided with spiral teeth 9 on its lower face and with a fin or rib 10 on its upper face, is located in an enlarged 80 slot or channel 11, directly beneath the slot 7. The fin 10 extends upwardly into the bottom of the slot 7 and receives a stud 12 projecting downwardly from the tongue 6, to removably lock the body of the gage 85 to the rack bar 8. The bottom of this channel 11 is cut away intermediate of its ends to expose the teeth on the rack bar 8, and these are engaged by one or more, in the present instance two, spiral toothed driving 90 pinions or worms 13, 14, on a shaft 15, supported in a split sleeve or bearing 16 fixed to the table support. To that edge of the gage body 5 toward the cutter, a fence 17 is pivoted, as shown at 18, 19, Fig. 1, so that 95 it may be thrown back out of the way of the workman when he is adjusting a block or plate for the first cut. The fence 17 has a dove-tail groove 20 extending longitudinally along its face for the reception of detachable extension pieces 21, 22, for the purpose of advancing the work edge of the gage to a point nearer the path of the cutter than the outer edge of the plate clamps 3 and 4, or either of them, to dimension 105 short and narrow work. These extension pieces and termed "stops" and are known in connection with the present subject matter as "pica stops," being made eighteen picas in length for reasons which will hereinafter 110 appear. They are each provided with a dove-tail tongue 23 to enable them to be

attached to and slid along the groove 20, and the dovetail tongue is locked to the stop by means of a screw-threaded shank 24 extending from the back of the tongue through 5 a socket 25, a set nut 26 on the outer end of the shank serving to clamp the stop to the tongue and the tongue to the walls of its groove. A spring 27 located between the nut and the bottom of the socket serves to 10 cushion the parts and take up lost motion as the stop is slid along the groove with the nut slightly loosened. The pieces or stops 21, 22, may be used singly or together as may be desired.

15 The body 5 of the gage is provided with a dove-tail groove 28 for the reception of the dove-tail head 29, of a bolt 30 which projects upwardly through an elongated slot 31 in a sliding bar or plate 32. The 20 plate 32 is provided with a shoulder 33 near one end, to engage a stop to be hereinafter described, and the bolt 30 is provided with a winged nut 34 to clamp the plate 32 to the body 5 of the gage in the desired position. The bar or plate 32 is guided along 25 the groove 28, by a shallow tongue 35 extending along the bottom of the plate into the neck of the groove 28.

The table 1 is provided with a dovetail 30 groove 36 running parallel with the groove 28, in the gage body 5, and in this groove there is seated the dovetail head 37 of a bolt 38 which extends up through a sliding block 39, the screw-threaded upper end of 35 the bolt 38 being provided with a tail nut 40 for clamping the block 39 to the table. The block 39 is guided along the groove 36, by a shallow rib 41 on its under side which projects into the neck of the groove 36. 40 The said block 39 is further provided with an offset 42, which lies in the path of the shoulder 33 on the sliding plate 32.

To lock the gage thus far described to the table 1, in the desired position, there is 45 provided a dovetail groove 43 in the table 1, for the reception of the dovetail head 44 of a bolt 45 which extends upwardly through the body 5 of the gage and is provided on its screw-threaded upper end with 50 a wheel nut 46. To assist in guiding the body of the gage along the table 1, the bottom of said body 5 is provided with a shallow rib 47 depending into the neck of the groove 43.

55 The dimensioning gage hereinabove particularly described and exclusive of the rack bar 10 and the pinions for driving it, may be used by executing its movements by the direct push and pull of the hand of the 60 workman, as follows:

The table having been drawn forward so as to leave room for positioning the plate and the dimensioning gage having been slid away from the cutter and its fence 65 turned upward and backward off the table,

the plate is first trimmed or edged by arranging it according to certain marks thereon, so that the edge toward the cutter will be cut in a right line along the indicated path. The plate is then clamped in position 70 and that edge is trimmed. The plate is then released and its trimmed edge placed against the straight edge at the front of the table with its end in position to receive a cut at right angles to that just made and in accordance with certain marks on the plate, if such there be and the cut is made. It is at 75 this point that the dimensioning gage comes into use for giving the plate the desired length and width. To accomplish this, the gage fence is turned down onto the table, and assuming that the length of the plate is sufficiently great to dispense with the use of the extension pieces, the engaging edge of the fence is adjusted the exact length of the plate 80 back from the path of the cutter and the block 39 slid along the groove 36 until its offset 42 engages a shoulder 48, see Fig. 1, on the back of the head of the body 5 of the gage. The block 39 is then clamped in position 85 and the dimensioning gage is moved toward the path of the cutter until the engaging edge of its fence reaches a point distant from the path of the cutter the exact 90 desired width of the plate. The sliding plate 95 32 is then released and slid along on the body of the gage until its shoulder 33 engages the offset 42 on the block 39, and is then clamped to the body 5 of the gage in that position. The plate already trimmed 100 along an adjacent side and end, is then placed with its squared end against the face of the gage and the gage moved back until the shoulder 48 engages the offset on the block, when the table may be moved forward 105 and the opposite end of the plate trimmed to give the plate the exact length desired. The table is drawn back, the plate is turned 110 with its trimmed side against the edge of the gage, the gage is moved forward until the shoulder 33 engages the offset on the block, and after clamping the gage to the table, the table is moved forward and the final side of the plate is trimmed, giving the plate the exact width desired.

115 No further adjustment is required for trimming successive plates to the same dimensions, as the stops, to wit: the block 42 and plate 32, determine these dimensions for each succeeding plate.

120 Whenever a group of plates of a different size is to be trimmed, the stops may be reset and satisfy the conditions for that group.

125 Of course if but a single plate were to be trimmed of any given size, there would be no necessity for utilizing the stop as the gage could be clamped in the two positions for length and width consecutively and the plate trimmed after each adjustment.

130 In order to relieve the workman from ad-

justing the gage by actual measurement and to furnish at the same time, if desired, adjustments in strict accordance with printers' points, I have provided gear for operating the dimensioning gage and for associating therewith a micrometer disk which may be in accordance with linear units of English measurement, if so desired, but which will be explained in connection with sub-divisions 5 with the printer's point as the standard.

10 The shaft 15, carrying the driving pinions 13, 14, hereinabove referred to, has also thereon a spiral toothed pinion 49 in mesh with a spiral toothed driving wheel or worm 50 on a shaft 51 supported in suitable bearings beneath the table support 52 and extending forwardly to a point in convenient reach of the operator at the front edger. The shaft 51, toward its front end, has keyed 15 thereon a bearing disk 53 which rests against the shoulder 54 on the shaft, and the rim of which engages an annular bearing face 55 on the inner side of a micrometer disk 56. The micrometer disk 56 is mounted to turn 20 on the shaft 51, when released from the disk 53, and its outer face 57 is subdivided into units having for their standard the printer's point which is about one-seventy second of a linear inch.

25 30 In proximity to the micrometer disk 56, there is a stationary disk 58 fixed to the table support and carrying an indicating line 59 thereon as the point of origin for measurement. The micrometer disk 56 is further provided with a knurled wheel 60 35 for conveniently rotating it when released, and exterior to this knurled wheel 60, there is keyed on the shaft a hand wheel 61, conveniently provided with a handle 62 for rotating the shaft 51. A nut 63 screwed on the 40 end of the shaft 51 against the hub of the wheel 61, serves to slide the hub of the wheel 61 against the hub of the micrometer disk and thereby force its annular bearing face 55 against the rim of the bearing disk 53, to lock the micrometer disk so that 45 it shall rotate with the shaft 51 when so desired.

50 In practice, the face 57 of the micrometer disk is subdivided by fine lines into equal spaces of such width that the rotation of the micrometer disk one space will, through the intermediate gear, advance the gage the distance of one-half of a printer's point, one 55 hundred forty-four of these spaces being indicated. Each second line is made a little longer than the one preceding it to indicate an advance of the gage one printer's point, each sixth line a little longer than the second and 60 fourth line to indicate an advance of the gage three printers' points, and each twelfth line a little longer than the sixth to indicate an advance of six printers' points or one-half a pica. These pica lines are numbered 65 1, 2, 3 and so on, up to 6. Furthermore,

each half pica receives a number summing up the spaces from zero up, namely, 6, 12 and so on up to 72.

70 Through the gearing hereinabove described, a complete rotation of the micrometer disk 56 will move the dimensioning gage forward six picas or seventy-two points. To facilitate the reading and hence the setting of the gage, a secondary micrometer disk 64 is provided and loosely 75 mounted on a shaft 65 set in a suitable bearing 66 beneath the table, the said shaft 65 having a spiral toothed pinion 67 thereon in mesh with a spiral toothed portion 68 on the shaft 51. The disk 64 has an inner annular 80 bearing face 69 which engages a disk 70, keyed to the shaft 65 and resting against a shoulder 71 on said shaft. A stationary disk 72 with its face in alinement with the face of the disk 64, is fixed to the support 66, 85 and has marked thereon, by a fine line, a point of origin 73, to coöperate with the subdivision of the micrometer disk 64. The outer portion 74 of the disk 64, of the micrometer is knurled on its cylindrical surface for convenience in manipulating the disk, and the said disk is locked to rotate 90 with the shaft by means of a nut 75 on the screw-threaded end of the shaft 65 which presses against a washer 76 keyed to the 95 shaft and resting against the hub of the micrometer disk 64, so as to force the micrometer disk against the bearing disk 70.

100 The said micrometer disk is furthermore formed in two sections, the one section 64 with the knurled portion 74, having a movement relative to an inner portion 77, as follows: The end of the disk 64, 74, is provided with an elongated curved slot 78 through which a clamp screw 79 extends, 105 and is tapped into the inner section 77. This screw 79 serves to clamp the two parts of the micrometer disk together or release them one from the other as may be desired.

110 In practice, the curved face of the micrometer disk 64, is subdivided into equal parts, each corresponding to a revolution of the primary micrometer disk 56, viz: six picas. As the disk is manipulated, it has fifteen of these six pica subdivisions. The 115 length of the slot 78 is such that if the clamp screw 79 be released, the part 64, 74 of the micrometer disk may be rotated on the inner part 77 without disturbing any of the other adjacent parts, a distance of three subdivisions or eighteen picas. The length of this slot coacts intimately with the extension pieces or stops 21, 22, hereinbefore described and is employed to set the micrometer to zero when the extension pieces or 120 stops 21, 22, are employed. For example, when the stops 21, 22, are placed in position on the working face of the gage, their length being eighteen picas, the primary micrometer disk and shaft connected there- 125 130

with, will be turned backward three revolutions to account for the length of said stops 21, 22. This will leave the primary micrometer disk at zero, but it will leave the secondary micrometer disk 64 three subdivisions from zero, viz: eighteen picas. All it requires then to set the secondary micrometer disk in harmony with the primary micrometer disk is to release the clamp screw 10 79 and turn the micrometer disk 64 the length of the curved slot 78 to bring it to zero ready for the work of dimensioning.

In operation, a plate having been alined and trimmed on a side and end and the 15 length and width of the plate having been determined upon, the primary disk is turned to place the dimensioning gage at the proper distance from the path of the cutters for the length of the finished plate and then to the 20 proper distance to determine the width of the finished plate, the dimensioning stops 39 and 32 having been manipulated as hereinabove described at each adjustment. The gage is now ready for performing the work 25 consecutively on a group of these dimensions without any further setting.

Particular attention is called to the structures hereinabove described which admit of the micrometer disks, both primary and secondary, being free to be rotated on their shafts independently of the shaft. This feature becomes of practical importance as follows: Cutters will wear and in sharpening and resetting they may not project exactly 35 to the positions which they originally occupied and hence an error in measurement would arise were there not means for accounting for this difference in position. To account for this difference, when a new cutter is placed in position, the gage is moved 40 forward into contact with the cutter and the micrometer disks are then released from their shafts and accurately adjusted with their zeros on the point of origin mark when 45 the disks are again clamped to the shafts and work again proceeds.

When the gage is used in connection with work which has no mark to indicate the line of cut along its edge other than the 50 subject, for example a picture, it is important that the plate be squared with respect to its subject, and to this end there is provided a subject squaring gage 80 hinged to an arm 81 to swing vertically, the arm 81 55 being hinged to a slide 82 provided with a clamp nut 83. The slide 82 is arranged to move along a dovetail groove 84 in an upwardly projecting rim or fence 85 of the table, the said slide 82 being provided with 60 a shallow downwardly projecting rib 86 which travels along the neck of the groove 84, the dovetail head 87 of a clamping bolt being arranged to travel along said groove 84, and the threaded end of the bolt ex-

tending through the slide 82 to receive the 65 nut 88. A tail nut 88 serves to lock the gage 80 to the arm 81 in the desired vertical adjustment to cause the gage to lie parallel with the table or with a plate thereon, no matter how thin or how thick the plate 70 75 may be.

The structure as hereinabove described is calculated to eliminate all doubt and uncertainty as to the accurate measurement 80 itself as it is constructed so that the measurements can be readily read and the parts are of such size and structure that they will prove durable and dependable while they have that refinement of action required of an instrument of precision.

While, as before said, the micrometer disks may be subdivided to indicate in accordance with other standards than the point system, the latter is desirable as the pica is invariably used as a unit of length in measuring the line of type and both dimensions of a printing plate.

What I claim is:

1. The combination with a work supporting table mounted to move forward and back to feed the work, a cutter and a rack bar free to move relative to the said table, of a dimensioning gage supported on the table in sliding adjustment toward and away from the path of the cutter, means 90 for connecting the rack bar with the gage through the table and means independent of the gage for supporting and operating the rack bar.

2. The combination with a work supporting table mounted to move forward and back to feed the work and provided with an undercut groove in its under side for receiving a traveling rack bar and with an opening extending from said groove through its upper face for receiving a connection between the rack bar and a dimensioning gage, of a cutter, a dimensioning gage supported on the table to slide toward and away from the cutter and means for holding the gage in its adjusted position, the said gage being constructed to work independently of a rack bar or to receive a connection with a rack bar at pleasure.

3. The combination with a work supporting table mounted to move forward and back to feed the work, and a cutter, of a sliding rack bar, a dimensioning gage supported on the table independently of the rack bar and having a freely removable connection with the rack bar to leave the upper surface of the table unobstructed, and means for engaging the sliding rack bar for operating the gage.

4. The combination with a work supporting table and a cutter, of a dimensioning gage movable on the table, a toothed rack connected with the gage and a plurality of

- spiral gears arranged to rotate in unison and engage the rack singly or collectively to operate the gage.
5. The combination with a work supporting table and a cutter, of a dimensioning gage movable on the table, a rack bar seated beneath the table and movable relative thereto, a connection between the rack bar and gage through the table, a spiral driving gear engaged with the rack bar, a drive shaft beneath the table geared to said spiral driving gear and a micrometer disk for indicating the extent of movement of the shaft.
10. The combination with a work supporting table and a cutter, of a dimensioning gage movable on the table, a micrometer disk and a connection through the table between the micrometer disk and gage, said connection including a shaft beneath the table on which the micrometer disk is mounted, a rack bar movable relative to the table, and spiral gear between the shaft and rack bar.
15. The combination with a work supporting table and a cutter, of a dimensioning gage movable on the table, a micrometer disk and a connection through the table between the micrometer disk and gage, said connection including a shaft beneath the table on which the micrometer disk is mounted, a rack bar movable relative to the table, and spiral gear between the shaft and rack bar.
20. The combination with a cutter, a dimensioning gage and means for accurately setting the gage a certain number of units of measure from the cutter, of an extension piece in coöperative relation to the gage and having a length corresponding to an exact number of said units of measure.
25. The combination with a dimensioning gage and means for extending it, of a micrometer disk, means for connecting it with the gage and means associated with the micrometer disk for permitting a movement of the disk independently of said connecting means, a distance corresponding in units to the gage extending means.
30. The combination with a dimensioning gage and means for extending it, of a micrometer disk, a disk provided with an elongated curved slot and associated with the micrometer disk to limit its movement to correspond with said gage extending means, a clamp screw extending through said slot for binding the disks together and means for connecting the said slotted disk with the gage.
35. The combination with a dimensioning gage and means for extending it, of a micrometer disk, means for connecting it with the gage and means associated with the micrometer disk for permitting a movement of the disk independently of said connecting means, a distance corresponding in units to the gage extending means.
40. The combination with a dimensioning gage and means for extending it, of a micrometer disk, a disk provided with an elongated curved slot and associated with the micrometer disk to limit its movement to correspond with said gage extending means, a clamp screw extending through said slot for binding the disks together and means for connecting the said slotted disk with the gage.
45. The combination with a dimensioning gage and a shaft geared thereto, of a primary micrometer disk for operating the

shaft and resettable with respect to the shaft, a secondary micrometer disk operated by the said shaft and means for advancing 55 or turning back the secondary disk without resetting the primary disk.

11. The combination with a support and a dimensioning gage thereon provided with an undercut groove in its face, of an extension piece and a traveling foot piece provided with a retaining head and with a screw-threaded shank extending through a portion of the extension piece and a nut for engaging the said shank to lock the extension piece in sliding adjustment to the gage.

12. The combination with a suitable support and a dimensioning gage thereon provided with an undercut groove along its face, of an extension piece adapted to rest 70 against the working face of the gage, a piece provided with a retaining head and with a screw-threaded shank extending through a portion of the extension piece, a spring surrounding said shank and a screw 75 for engaging the shank and locking the extension piece yieldingly to the gage.

13. The combination with a suitable support and a dimensioning gage thereon, of an extension piece having a length equal to 80 an exact number of printers' points, means for removably securing the extension piece to the face of the gage, a micrometer subdivided according to printers' points for controlling the movement of the gage, and 85 means for resetting the micrometer to zero when the extension piece is employed or removed.

14. The combination with a suitable support and a cutter, of a dimensioning gage 90 and a squaring gage arranged to slide along the support and vertically adjustable, said gage being parallel to said table in all adjusted positions thereof over the support to align the work for the dimensioning gage. 95

In testimony, that I claim the foregoing as my invention, I have signed my name, in presence of two witnesses, this twenty-first day of April, 1915.

VERNON ROYLE.
